UNITED STATES PATENT OFFICE.

ELMER E. F. CREIGHTON, OF SCHENECTADY, NEW YORK, ASSIGNOR TO GENERAL ELECTRIC COMPANY, A CORPORATION OF NEW YORK

TRANSMISSION-LINE.

1,131,216.

Specification of Letters Patent. Patented Mar. 9, 1915.

Application filed September 11, 1912. Serial No. 719,714.

To all whom it may concern:

Be it known that I, ELMER E. F. CREIGHTON, a citizen of the United States, residing at Schenectady, county of Schenectady, 5 State of New York, have invented certain new and useful Improvements in Transmission-Lines, of which the following is a specification.

My invention relates to systems of electrical distribution and more particularly to 10 transmission lines which extend for many miles and are subjected to varying influences, such as thunder storms and similar disturbances which tend to produce on the 15 transmission line abnormal voltages, surges and similar destructive phenomena commonly included under the term lightning.

Most of the surges, oscillations and similar disturbances which appear upon transmission lines appear to be the result of inductive action rather than of direct lightning 20 strokes. There are various causes for these disturbances, but in very many cases the presence of a storm cloud in the vicinity of 25 a transmission line will set up destructive surges and oscillations on the transmission line. Usually such a cloud is in inductive relation to only a comparatively small extent of the transmission line, but the inductive 30 disturbance due to the presence of the cloud quickly builds up into destructive surges and oscillations, owing to the ease with which surges and oscillations can travel on the ordinary transmission line. There 35 also appears to be a tendency for lightning discharges in the vicinity of the line to induce upon a considerable portion of the line a very high momentary voltage which is then distributed along the line with comparatively 40 little loss and appears throughout the whole length of the line in the form of surges and oscillations which are destructive at their first appearance, or else are built up by repeated inductive effects from the 45 cloud until they become destructive. These oscillations and surges are transmitted along the line under favorable conditions, as the ordinary transmission line offers very little damping effect to electrical vibrations. Its 50 impedance is distributed either uniformly, or else in the form of substantially equal impedance placed at regular intervals along the line. It will vibrate electrically with but slight damping, in much the same way 55 that a stretched string, either unloaded or

uniformly loaded, will transmit vibrations with but little loss or damping.

One object of my invention is to prevent on a transmission system the development of oscillations and similar abnormal conditions by the inductive effect of a highly charged cloud or of a stroke of lightning in the vicinity of the transmission line. To accomplish this result I construct the line in such a manner that oscillating and transitory disturbances, if transmitted along the line at all, are quickly damped out. The line is made of a character unfavorable to the transmission of such disturbances, and damps them out in much the same way as an 60 irregularly loaded stretched string damps out vibrations in it. To secure the desired effect, I make the conductors of the transmission system electrically irregular by varying the impedance of the conductor in 65 an irregular manner. High frequency potential waves can travel along such a conductor only with the greatest difficulty, and standing waves cannot be added to the potential wave to produce destructive voltage 70 peaks. The conductor may be made electrically irregular by impedances strung along the conductor at irregular intervals, or by impedance differing in amount and strung along the conductor at regular intervals, or in other equivalent ways. 75

Another difficulty encountered in transmission lines arises from the fact that the insulators used on the ordinary transmission line are all of substantially the same 80 size. When the destructive surges and oscillations approach a value great enough to cause discharges to ground a discharge or 85 flashover may occur at almost any of the insulators. After such a breakdown or flashover, the entire line must be inspected in 90 order to determine at which insulator the flashover to ground occurred. This extended inspection requires much time and is 95 objectionable. If the destructive effect of the surges and oscillations cannot be entirely eliminated, it is desirable that the discharges and flashovers to ground shall take place at selected insulators along the line, so that the discharges shall occur at known 100 points on the line, and another object of my invention is to cause the flashovers and discharges to ground to take place at certain selected insulators. To this end, I place impedance near selected points to cause an ab- 105 110

normal voltage in the conductor to discharge at selected insulators rather than over the others. In this way the other insulators are protected and the discharges or flashovers occur at definite and known places where devices may be used to prevent actual damage.

A further object of my invention is to provide an improved form of inductance or impedance device which is of simple and rugged construction and can easily be inserted in series with the conductors of a transmission system.

My invention will best be understood in connection with the accompanying drawing which merely for purposes of illustration shows diagrammatically some of the forms in which my invention may be embodied and in which—

20 Figure 1 shows semi-diagrammatically an improved form of inductance, particularly suitable for being connected in series with the conductor of a transmission line; Fig. 2 is a diagram showing a transmission line 25 with inductances distributed at irregular intervals along the conductor; Fig. 3 is a diagram showing another form of transmission line embodying my invention; Fig. 4 is a diagram showing the effect of a conductor 30 embodying my invention upon a surge or oscillation appearing upon the conductor; and Fig. 5 is a view in perspective of a poly-phase transmission line embodying my invention.

35 My invention may be embodied in various forms of transmission lines, one form being diagrammatically shown in Fig. 2, in which the conductor 1 of the transmission line is provided at irregular intervals with concentrated inductances 2 connected in series with the conductor. By placing these inductances at irregular intervals, I break up the conductor into adjoining sections which are electrically dissimilar so that the conditions 40 are made as unfavorable as possible for the development of stationary waves and for the transmission of surges and oscillations. Even though the section or length of the conductor in which the oscillation first appears should be favorable to the development 45 and transmission of the oscillation, the next section would not be and as a result the oscillation or surge would quickly be damped out. The varying lengths and differing electrical characteristics of the adjoining sections of the conductor render the development of high frequency harmonics practically impossible.

50 Substantially the same result may be obtained in the manner shown in Fig. 3, in which inductances 3 are distributed at uniform distances apart along the conductor, but each inductance differs in amount from each adjacent inductance. The electrical effect is the same as in the form shown in Fig.

2 and as each section of the line differs in impedance and other electrical characteristics from the adjoining section, oscillations and surges cannot travel for any distance along the conductor.

While I do not wish to advance any theory of operation the effect which is probably produced is shown diagrammatically in Fig. 4, in which the dotted line 4 shows a wave of potential set up by an inductive 75 discharge in the vicinity of the conductor. As this wave of potential travels along the conductor and encounters one of the inductances 2 or 3 it is broken up to some extent and reduced in amplitude and as it passes 80 into the next section where conditions are unfavorable for its amplitude, being increased by resonance it is again broken up and reduced by the action of the next inductance and so on, with the result that oscillations and surges are quickly damped out and kept below destructive values. Some idea of the value of these impedances during the formation of a lightning stroke may be gained by the following theoretical explanation:—Before the quantity of electricity in the cloud gathers to one central point and breaks through the atmosphere in a bolt to earth, the charges on the line are distributed along the line on the sections formed by the 85 choke coils. As the lightning charge in the cloud gathers at one point, the corresponding induced charges on the line follow the movement of the charges in the cloud and also gather at one point. If the line 90 consists, as it generally does, of a straight wire the charge can be moved at practically the speed of light, that is, 180,000 miles per second. These induced charges on the line will rush together from different directions and 95 will pile up as one high peak. With the presence of a choke coil, however, the electrostatic charge located between choke coils will be greatly retarded in its movement by the time constant of the choke coil. 100 The object is to make these time constants greater than the time constants of the discharge from the cloud so that the discharge will have taken place and reversed before the charge in the line can follow it. This 105 will keep the charge in the line more distributed and broken up into smaller parts and thus prevent the tremendous accumulation at one point on the line. If, as shown in Fig. 1, the supporting material between 110 the terminals is properly chosen with a high resistance, considerable part of the energy in the localized charges on the line may be absorbed by the fact that they suddenly endeavor to pass through the choke coil.

115 The impedances which I prefer to insert in the conductors of the transmission line are preferably made in the form of inductance coils having some resistance in shunt. These coils I prefer to construct in the man-

ner shown in Fig. 1. Each end of the coil 2 is secured to a metal terminal 5 which is connected to the conductor 1. The terminals 5 are rigidly secured to the ends of a member 6 which has a certain amount of resistance, and is in shunt to the coil 2. The member 6 is preferably constructed to withstand the tensile stress exerted upon it by the conductor. As a result of this construction the coil 2 is rigidly secured at the ends to the metal terminals 5, while the longitudinal stress exerted by the conductor is taken up by the member 6, which not only forms a core for the coil 2 and supports it in case 10 for any reason the coil should sag, but also acts as a resistance shunt to the inductance coil. An impedance constructed in accordance with my invention is cheap and rugged, and amply able to withstand the usage to 15 which it is subjected when connected in a transmission line.

I prefer to arrange the impedances in the conductors of the transmission line in the manner shown in Fig. 5, and as shown in 20 this figure one of the impedances is placed close to a selected insulator 7 where in case the conditions are such that the charges cannot be held back as the main stroke takes place (see previous theoretical description) 25 the flash over or discharge to ground will occur at this particular point. Under such conditions, the presence of the inductance immediately adjacent the selected insulator produces a tendency to flash over at the selected insulator in preference to the other insulators, and consequently the flash over 30 or discharge to ground is much more apt to occur at the selected insulator than at the others.

40 My invention may be embodied in many other forms than the precise arrangement disclosed and I, therefore, do not wish to limit my invention to the precise arrangement disclosed except in so far as it is limited by the scope of the appended claims.

45 What I claim as new and desire to secure by Letters Patent of the United States, is:—

1. A transmission line comprising a conductor having impedance irregularly distributed along said conductor to render equal and adjacent lengths of said conductor electrically dissimilar and the whole conductor electrically irregular.

2. A transmission line comprising a conductor having impedance unsymmetrically distributed along said conductor at compar-

atively great intervals to render every section of said conductor electrically different from an adjoining section of equal length and said conductor electrically irregular throughout its length.

3. A transmission line comprising a conductor, and impedance unsymmetrically distributed at comparatively great intervals along said conductor to cause said conductor to be irregularly loaded with impedance.

4. A transmission line comprising a conductor, and impedances equal in amount distributed along said conductor at markedly unequal distances from one another.

5. A transmission line comprising a conductor, and impedances equal in amount and distributed along said conductor so that the distance between each impedance and the next on one side differs by a substantial amount from the distance between said impedance and the next on the other side.

6. An impedance device for insertion in the conductor of a transmission system comprising a poorly conducting member having sufficient tensile strength to withstand the tensile stress exerted by the conductor and provided with a metal terminal at each end, an inductance coil encircling said member with its ends secured to said terminals, and means connecting said terminals in series relation with said conductor.

7. An impedance device for the conductor of a transmission system comprising an inductance coil shunted by a poorly conducting core of sufficient tensile strength to withstand the pull of the conductor, a metal terminal secured to each end of said core and of said coil, and means connecting said terminals in series relation with said conductor.

8. A transmission line comprising a conductor and inductance coils shunted by resistance distributed along said conductor to cause the impedance of said conductor to vary irregularly.

9. A transmission line comprising a conductor, and impedance devices of equal value distributed along said conductor at unequal intervals, each of said devices comprising an inductance shunted by resistance.

In witness whereof, I have hereunto set my hand this 9th day of September 1912.

ELMER E. F. CREIGHTON.
